UNITED STATES PATENT OFFICE.

MAX M. COHN, OF PIEDMONT, CALIFORNIA.

LOOSE-LEAF-DISPENSING DEVICE.

1,130,571.

Specification of Letters Patent.

Patented Mar. 2, 1915

Application filed July 22, 1914. Serial No. 852,395.

To all whom it may concern:

Be it known that I, MAX M. COHN, a citizen of the United States, residing at Piedmont, in the county of Alameda and State of California, have invented new and useful Improvements in Loose-Leaf-Dispensing Devices, of which the following is a specification.

This invention relates to a container and dispenser for interfolded sheets of paper, or the like.

The objects of the present invention include the provision of a carton which is particularly constructed to serve as a container and wrapper for a stack of interfolded sheets of paper towels or the like; and to operate either as a holder and dispenser itself, or as an adjunct to a separate dispensing device; the provision of such a dispensing device to act as a receptacle for the carton, with interfolded towels, from which the towels may be withdrawn as used; and of means on the holder for supporting the interfolded sheets within the carton, when this is in position within the holder, and which will also prevent the lowermost interfolded sheets in the carton from becoming jammed or wedged.

Further object will hereinafter appear.

The invention consists of the parts and the construction and combination of parts as hereinafter more fully described and claimed, having reference to the accompanying drawings, in which —

Figure 1 is a perspective of a carton showing the method of folding the sheets. Fig. 2 is a perspective of the front of a full container. Fig. 3 is a rear view of the container empty.

A represents a carton adapted to contain a stack of paper towels, which are so interfolded, with relation to each other, that the withdrawal of one towel will withdraw a portion of the next towel, thus forming a finger hold wherewith to grasp and withdraw each towel in succession. The carton consists of a single sheet of card-board folded to form a back section 2, short upturned front bottom section 3 and a foldable front top flap section 4; sufficient space being provided between the flap and bottom section to form what might be called a discharge slot 5, through which the interfolded towels may be withdrawn, one at a time. The carton proper is provided as a holder for the

towels and also serves as a wrapper in which the towels may be shipped from the dealer to the consumer.

The paper towels may be folded and stacked in any suitable manner within the carton, but preferably as shown in Figs. 3 and 4; that is, each paper towel or sheet is folded adjacent to its center, as shown at 6, so that the sheet is divided into two portions of unequal length, as indicated at 7 and 8. The longer section 7 is then folded in an opposite direction to sheet 8, near the outer end, to form a short end fold and finger-hold 9. The sheets thus folded into sections 7, 8 and 9 are then interleaved in such a manner that the short section 8 of one sheet will always be interposed between the long section 7 of the two succeeding sheets. The sheets when thus interfolded may be pulled out from under the stack, one by one, and will, when removed, always free the large section 7 of the following sheet, or, in other words, pull it out to a position where it may be easily grasped.

In practice, the folding and interleaving is done by machinery, not here shown, in which the paper is fed in continuous sheets from two rolls and cut alternately and interfolded. They are then stacked, not in a square column, but diamond shaped, and inserted into the carton: the diamond shape of the package bringing the interfolded leaves into vertical position so they stand parallel with the front wall 4 of the carton with the lip 9 of a sheet protruding through the slot 5.

The filled carton with its sheets is held in position by passing a paper band 10 around it, and pasting the ends together. While the carton A may be used as a dispenser, still most people prefer a permanent fixture into which the carton may be inserted. In such cases I provide a holder consisting of a case, preferably of sheet metal, having a front 11 with a slot 12 formed therein extending across near its lower end, and coincident with slot 5 of the carton. The holder is closed at the sides as at 13 and may be open at the back except for a pair of rear curved guides 14. Guides 14 are secured at their upper ends to a cross rod 16 and have their lower ends curved, as at 17, and extended inwardly to join the front section at an acute angle below slot 12; this distance from the lower edge of slot 12 to the point

of juncture of the guides with the front being equal approximately to the length of flap 3 of the carton A. A rod 19 similar to rod 16 is provided at the lower 5 end of the casing at the back, on which is slidably mounted the clips 20 by which the casing may be secured to a suitable support. The slidable mounting of the clips 20 permits them to be moved along the rods to a 10 position where they may be brought into register with the studding in a wall or like support.

A casing constructed as shown is cheap to manufacture and light in weight. As the 15 top, bottom and rear sides of the casing are entirely open, it can, therefore, be secured to practically any kind of a support, and in any place within easy reach of a wash-stand, and by reason of the small 20 amount of material used in manufacture and its simplicity in construction may practically be given away to users of carton-wrapped towels.

In practice, when loading the holder, the 25 band 10 is removed and the free end 9 of a towel made to project through the carton slot 5. The carton is then dropped into the holder just described; the curved section 17 of the rear guides causing the back section 2 30 of the carton to assume the same curvature as the guides, so that the towel lip 9 is automatically fed through the slot 12. By reason of the peculiar diamond shape of the stock and carton, all the towels assume a 35 substantially vertical position parallel with the front 11 of the holder. To keep the carton front from slipping down as the towels are used up, and partly or wholly closing the slot 12, I employ suitable means, as a 40 pair of spring arms or fingers 22 which exert sufficient pressure on the top of the carton to force it backward against the rear guides 14. In order to prevent the lowermost 45 towels from becoming wedged and pinched at the sharp angle formed at the point of intersection of the back 2 and front 3 of the carton, when the latter is dropped into the holder, I preferably make one or more notches 23 in the lower edge of the carton 50 to expose the bottom edges of the lowermost and forwardmost towels, and provide the brackets 24 on the front section of the holder, which brackets fit into notches 23 and serve to support said front bottom 55 towels from dropping into where they might have a tendency to become jammed or pinched.

The provision of the carton is of great importance as it permits the holder to be 60 filled quickly without any trouble or inconvenience. It furthermore prevents all liability of disarranging the interleaved towel sections and also insures delivery of a given quantity.

65 The special fixture is important because

the wedge-like or curved shape given to the upper and lower ends of the carton by the curved guides at one end and by the spring fingers at the other, forces the stacked sections or leaves in the upper and lower end 70 into a vertical position, while the intermediate section of towels are permitted to assume a more or less diagonal position. They will thus not only occupy a much narrower space, but the weight of the entire stack is 75 practically all taken up by the upper end of the curved guides, as indicated by arrow a, leaving the lowermost towels free to be drawn out without laceration or being severed.

Having thus described my invention what I claim and desire to secure by Letters Patent is—

1. A paper towel dispenser and holder for cartons including a case having a pair 85 of spaced guides at its rear which guides have curved lower ends, and a pair of spring fingers connected to the case at the top thereof and having free portions aligned with the space between the guides adapted 90 to engage and press the front of the carton against said guides.

2. A paper towel dispenser and holder for cartons including a case having a pair 95 of spaced guides at its rear which guides have curved lower ends, and a pair of spring fingers connected to the case at the top thereof and having free portions aligned with the space between the guides adapted to engage and press the front of the carton 100 against said guides, and a carton engaging bracket at the front lower end of the casing adapted to be received in a notch provided therefor in the carton.

3. A paper towel dispenser and holder for 105 cartons including a case having rear guiding means for the carton rear, and means to engage the top portion of the carton to force same against said guiding means to thereby assume the greater part of the 110 weight of the carton.

4. A paper towel dispenser and holder for cartons including a case having a withdrawal slot and a projection below the slot and at the front of the case, said projection 115 being adapted to be received in a notch at the carton bottom so as to engage the towels to hold the same above the carton bottom.

5. A paper towel dispenser and holder for cartons including a case having a withdrawal slot and a pair of spaced bracket members below the slot and adjacent the front of the case, said members being adapted to be received in a pair of notches provided therefor at the carton bottom so as to 120 engage the towels to hold the latter above the carton bottom.

6. A dispensing device including a case having sides and an open back, a rod connected to the sides and extending across the 130

back, and fastening devices in the open back engaging the rod and being shiftable along the length of the rod.

7. A paper towel dispenser and holder for 5 cartons including a case having a withdrawal slot, and means at the base of the case to engage within the carton to support the towels above the carton bottom.

8. A paper towel dispenser and holder for 10 cartons including a case having a withdrawal slot, means at the base of the case to engage within the carton and to support

the towels above the carton bottom, and means adapted to frictionally engage the top of the carton to assume the greater part 15 of the weight of the carton.

In testimony whereof I have hereunto set my hand in the presence of two subscribing witnesses.

MAX M. COHN.
